AUTOMATIC DRAIN

Filed Feb. 6, 1931

UNITED STATES PATENT OFFICE

GEORGE H. LECARPENTIER, OF CHICAGO, ILLINOIS, ASSIGNOR, BY DIRECT AND MESNE ASSIGNMENTS, TO ALBERT G. McCaleb, OF EVANSTON, ILLINOIS

AUTOMATIC DRAIN

Application filed February 6, 1931. Serial No. 513,936.

My invention relates to automatic drains and contemplates and provides instrumentalities which automatically discharge liquid from the bottom of the radiator or other low point in the cooling system of an internal combustion engine whenever the relationship between the temperature of the liquid and its specific gravity is such that freezing of the liquid is imminent.

10 The specific embodiment of my invention herein shown and described is intended for use in connection with an engine cooling system wherein the circulating liquid is an aqueous solution of alcohol. But I wish it to be understood that the apparatus of the present invention readily may be modified to handle circulating liquids the susceptibility of which to freezing becomes greater as the specific gravity of the liquid becomes less. 15 The susceptibility to freezing of an aqueous solution of alcohol, of course, becomes greater as its specific gravity increases, that is, as the alcohol content of the solution becomes less, due usually to its vaporization and escape 20 from the system.

In the accompanying drawings:

Figure 1 is a view partly in vertical section and partly in elevation illustrating the apparatus of the present invention applied to the lower part of a radiator, which may be regarded as forming a part of the cooling liquid circulating system of the internal combustion engine of an automotive vehicle;

Figure 2 shows the housing of the apparatus of the present invention in horizontal section, the section being taken on the line 2—2 of Figure 1, the parts within the housing being shown in top plan but with a part of the float or buoyant member broken away to reveal the elements which lie beneath it;

Figure 3 is an enlarged sectional detail view taken on the line 3—3 of Figure 1; and

Figure 4 illustrates a modified form of top plate or cover with which the housing may be provided when it is desired to have a forced circulation of the cooling liquid through the device of the present invention whenever the engine is operating.

Similar characters of reference refer to similar parts throughout the several views.

In the drawings reference letter A represents the lower part of a radiator forming part of the cooling liquid circulating system of the internal combustion engine of an automobile vehicle. At B is shown a drain pipe 55 extending from the lower end of the radiator, and at C is shown a cock for the drain pipe B, this cock being left in the open position when the device of the present invention is in use.

60 The apparatus of the present invention comprises a housing 10, conveniently rectangular in horizontal section, which is provided with a top plate or cover 11 held in position by screws 12 and lock washers 13, a sealing gasket 14 preferably being inserted between the top plate and the upper edge of the housing as shown.

The cover plate is provided with an upwardly extending hollow central boss which 70 has threaded engagement with the housing of the cock C and affords communication between the interior of the housing 10 and the lower part of the radiator A.

If desired, the top plate or cover may be 75 provided with an aperture 15 normally closed by a threaded plug 16 having associated therewith a lock washer 17, the purpose of the aperture 15 being to facilitate the elimination of an air pocket at the top of the housing 10 80 when liquid initially is permitted to flow from the radiator into the housing 10. The aperture 15 is, of course tightly closed when the apparatus is in use.

Pivotedly mounted within the housing 10 is 85 a float or buoyant member 18, this float or buoyant member conveniently being hollow, formed of sheet metal, and being generally rectangular in shape, as illustrated.

90 Rigidly secured to the lower left hand corner of the float or buoyant member 18, by solder, brazing or in other convenient manner, is a shaft 19 having its ends journalled, as is most clearly shown in Figure 2. Referring 95 to Figure 2, it will be seen that one end of the shaft 19 is received in the bore of a boss 20 formed integrally with the housing 10 and that the other end of said shaft is received in the blind bore 21 of a plug 22 which has 100

threaded engagement with the housing side wall by which it is carried.

The float or buoyant member 18 is provided with a spring 23 which resists the buoyant tendency of the member 18, this spring conveniently being a leaf spring having its lower end secured to the member 18 by solder or by brazing, the upper end of said spring bearing against and having sliding contact with the adjacent end wall of the housing 10. It will be understood, therefore, that the float or buoyant member 18 will assume a position determined by the specific gravity of the cooling liquid received by the housing 10 from the lower part of the radiator A. When the specific gravity of the liquid is low, the float or buoyant member will lie at or about the position shown in Figure 1. As the specific gravity becomes greater, the unpivoted end of the float or buoyant member takes a higher position by movement in opposition to the action of the spring 23.

Attached by solder, brazing or the like to the under side of the float or buoyant member, preferably at or near the shaft 19, is a bi-metal or thermostatic strip 24, the free end of which is bifurcated at 25 to receive the stem 26 of a valve member 27. Since the bi-metal or thermostatic strip is immersed in the liquid within the housing 10, the free end of the said strip will assume a position dependent upon the temperature of the liquid as and for reasons well known to those skilled in the art.

In the present instance, it being contemplated that the cooling liquid is an aqueous solution of alcohol, the bi-metal or thermostatic strip is so constructed that its free or bifurcated end will move toward the float or buoyant member 19 in response to a decrease in temperature and will move away from the same in response to an increase in temperature.

The valve member 27 normally co-operates with a tapered seat 28 formed in a downwardly projecting hollow boss formed integrally with the bottom of the housing 10. A light coil spring 29 encircling the valve stem 26 and acting between the valve member 27 and a valve stem guide 30, normally holds the valve member in a position to prevent the escape of liquid from the housing 10.

The valve stem guide 30 is conveniently a metal annulus having a press fit in the position shown. At its upper end the valve stem 26 is provided with a head 31 which may be engaged by the thermostatic strip to lift the valve member 27 from its seat and thus permit the escape of liquid from the housing 10 when, due to an increase in the specific gravity of the cooling liquid, or a decrease in the temperature of same, or both, the liquid is in danger of freezing.

The spring 23 and the bi-metal strip 24 are so constructed and arranged, in relation to each other and to the float or buoyant

member 18, that the bifurcated end of the bi-metal strip will engage the valve stem head 31 to unseat the valve 27 and thus permit the escape of liquid from the housing 10 whenever the relationship between the temperature of the liquid and its specific gravity is such as to predict the imminent danger of freezing.

The housing 10 should form the lowest part of the liquid circulating system to which it is applied. The connection of the housing with the lowermost part of the radiator of an engine cooling system, and the location of the housing beneath the radiator as shown, ordinarily will insure that the liquid in the housing 10, or at any rate the liquid in the lowermost part of the housing 10, will be the lowermost liquid in the cooling system.

It will be noted that the thermostatic element 24 is located very closely to the bottom of the housing 10, and is thus subjected to the temperature of the coldest liquid in the circulating system.

Let us assume that an automobile engine, the cooling liquid circulating system of which includes the improvements of the present invention, is left parked and that due to a rapid fall in atmospheric temperature, the liquid in the lowermost part of the cooling system, that is to say the liquid in the bottom of the housing 10, is in danger of freezing. The operation is as follows:

The float or buoyant member 18 having assumed a position corresponding to the existing specific gravity of the liquid, the bifurcated end of the bi-metal strip moves upwardly as the temperature of the liquid in which it is immersed becomes less. As or slightly before the temperature of the liquid in relation to its specific gravity, becomes such that the liquid is in danger of freezing, the bi-metal strip engages the valve stem head 31 and unseats the valve 27 to permit the coldest water to drain from the housing 10. As soon as the coldest water has been discharged and warmer water takes its position around the bi-metal strip 24, the free or bifurcated end of the strip moves away from the float or buoyant member 19, and may thus move sufficiently to permit the closure of the valve 27. Ordinarily, when the decrease in atmospheric temperature is not too rapid, the apparatus of the present invention functions only from time to time to permit the discharge of the coldest liquid in the circulating system, that is, the liquid at the lowermost point of the system, whenever that coldest and lowermost liquid is in danger of freezing. Of course, if the temperature of the liquid throughout the system is such that all of it is in danger of freezing, the float or buoyant member 18 and the thermostatic strip carried thereby will function and co-operate to hold the valve 27 open un-

til all of the liquid has been drained from the system.

Ordinarily, due to the turbulence of liquid in the cooling system when the engine is operating, the specific gravity of that part of the liquid in the system occupying the housing 10 will be typical of the specific gravity of the liquid throughout the system. If in any case, however, it is found that the connection between the radiator and the housing 10, which is afforded by the drain pipe B, is not sufficient to keep the liquid in the housing 10 representative of all of the liquid in the system so far as the specific gravity is concerned, the apparatus of the present invention may be modified by substituting the cover or top plate 11-a of Figure 4 for the top plate or cover shown in Figure 1. The top plate 11-a differs from the top plate 11 only that it is provided with nipples 32 and 33 adapted for connection with small hose conduits 34 and 35, respectively. When the housing 10 is provided with a cover plate such as indicated at 11-a, the hose 34 may be connected with the circulating pump of the engine on the pressure side thereof, and the hose 35 may be connected into the system at some point remote from the circulating pump. This arrangement insures that there will always be a more or less definite circulation of liquid through the housing 10 when the engine is in operation, thus doubly insuring that at all times the specific gravity of the liquid in the housing 10 will be truly representative of the specific gravity of the liquid throughout the system.

Having thus illustrated and described a preferred embodiment of my invention, what I claim as new and desire to secure by Letters Patent of the United States, is:

1. In combination with the liquid circulating system of an engine, means operating in accordance with the specific gravity of the liquid in said system, means operating in accordance with the temperature of same, and a drain valve influenced by the conjoint operation of the two means aforesaid.
2. In combination with the liquid circulating system of an engine, a thermostatic element subjected to the temperature of the liquid in said system and operating in accordance therewith, a drain valve adapted to be influenced by said thermostatic element, and a buoyant member located in said liquid and adapted to take a position depending upon the specific gravity of the liquid, said thermostatic element being carried by said buoyant member.
3. In combination with the liquid circulating system of an engine, means movable in accordance with the specific gravity of the liquid in said system, means movable in accordance with the temperature of same, and a drain valve responsive to movements of the two means aforesaid.

4. In combination with the liquid circulating system of an internal combustion engine, a drain valve for said system, a thermostatic element adapted to open said drain valve when a certain relationship exists between the temperature and specific gravity of the liquid in said system, and means, operating in accordance with the specific gravity of the liquid, carrying said thermostatic element.

5. In combination with the liquid circulating system of an engine, a drain valve for said system, a thermostatic element adapted to open said drain valve, and means operating in accordance with the specific gravity of the liquid for varying the temperature at which the thermostatic element will open the drain valve.

6. In combination with a liquid circulating system of an engine, a buoyant member in and movable in response to the specific gravity of the liquid in said system, a drain valve adapted to be operated by such member, and a temperature responsive member, interposed between said buoyant member and said drain valve, adapted to determine whether or not the drain valve will be open when the buoyant member has assumed any given position.

7. In combination with an engine circulating system including a radiator, a chamber connected with the lower part of the radiator and adapted to receive liquid therefrom, a buoyant member in said chamber adapted to assume a position depending upon the specific gravity of the liquid in said chamber, a thermostatic strip carried by said buoyant member and immersed in the liquid in said chamber, and a drain valve in said chamber adapted to be operated by said thermostatic strip whenever the relationship between the temperature of the liquid and the specific gravity of same is such that freezing of the liquid is imminent.

8. In combination with an engine circulating system including a radiator, a chamber connected with the lower part of the radiator and adapted to receive liquid therefrom, a buoyant member in said chamber adapted to assume a position depending upon the specific gravity of the liquid in said chamber, a thermostatic strip carried by said buoyant member and immersed in the liquid in said chamber, and a drain valve in said chamber adapted to be operated by said thermostatic strip whenever the relationship between the temperature of the liquid and the specific gravity of same is such that freezing of the liquid is imminent, said drain valve having a lost motion connection with said thermostatic strip.

9. In an apparatus of the class described, a housing, a buoyant member within the housing, a thermostatic element carried by said buoyant member, and a drain valve for said housing operatively connected to said

thermostatic element and subject to the joint influence of the thermostatic element and the buoyant member.

10. In combination with the liquid circulating system of an engine, a buoyant member immersed in the liquid in said system and adapted to take a position varying with the specific gravity of said liquid, a thermostatic element associated with said buoyant member and immersed in the liquid in said system, and a drain valve for said system subject to the joint influence of said buoyant member and said thermostatic element.
11. In combination with a liquid circulating system of an engine, a buoyant member immersed in the liquid in said system and adapted to assume positions corresponding to the specific gravity of the liquid, a thermostatic element carried by said buoyant member and movable therewith, and a drain valve for said system having lost motion connection with said thermostatic element and being adapted to be opened under the joint influence of the buoyant member and the thermostatic element.
12. In combination with a liquid circulating system of an internal combustion engine, a buoyant member immersed in the liquid in said system and adapted to assume positions corresponding to the specific gravity of the liquid, a spring opposing the buoyant tendency of said member, a thermostatic element carried by said buoyant member, said thermostatic elements being immersed in the liquid of said system, and a drain valve for said system adapted to be opened by the joint action of said buoyant member and said thermostatic element.
13. An automatic drain comprising a liquid receptacle, means movable in response to the specific gravity of the liquid in said receptacle, means movable in response to changes in the temperature of said liquid, and a drain valve for said receptacle influenced by the conjoint operation of the two means aforesaid.

In witness whereof, I hereunto subscribe my name this 31st day of January, 1931.

GEORGE H. LECARPENTIER.
